THE UNITED STATES OF AMERICA. 1334 X

JULY 7, 1810

To all to whom these Letters Patent shall come:

John

Benjamin Parry, a citizen of the United States, hath alleged that he has invented a new and useful improvement being a Machine for drying Corn & Grain of all kinds, and also for drying malt, meat, & other substances

such improvement is stated not to have been known or used before his application; has affirmed to the undersigned that he is the true inventor or discoverer of the said improvement.

He hath paid to the treasury of the United States, the sum of thirty dollars, delivered a receipt therefor, and presented a petition to the Secretary of State, signifying a desire of obtaining an exclusive right to the said improvement, and praying that a patent may be granted for that purpose.

Accordingly to the said Benjamin Parry his heirs, executors, and administrators, and to his assigns, he is granted a patent for the seventh day of July 1810.

for improvement no description whereof is given in the words, but in Benjamin Parry himself, in the form hereof agreed, and is made a part of the patent.

In witness whereof, I have caused these Letters Patent, and the Seal of the United States, to be hereunto affixed.

GIVEN under my hand, at the city of Washington, on the seventh day of July, in the year of our Lord, one thousand eight hundred and ten, and of the independence of the United States of America, the thirty-fifth.

James Madison

BY THE PRESIDENT.

As Smith
Secretary of State

I DO HEREBY CERTIFY, That the foregoing Letters Patent were delivered to me on the seventh day of July, in the year of our Lord, one thousand eight hundred and ten, to be examined, and I have examined the same, and find them conformable to law, and proper to be issued, and I do issue them to the said Benjamin Parry, to the intent and purpose contained in the patent, and to the intent and purpose of the same to the Secretary of State, within fifteen days from the time of issue, to wit: On this seventh day of July, in the year of our Lord, one thousand eight hundred and ten.

John Rodney
Attorney General of the United States.

De Schoule

Colle of Seijoull referred to in these Letters patent and
making part of the same, containing a description in the words of the said Benja
and Carry himself of his Machine for drying Corn and Grain of all kinds, and
also, for drying Malt, meat, and other substances.

The machine is intended for the use of Distilleries and Breweries and
be mounted within an attached structure and the machinery communicating
with it by the water or wind which turns the belt or otherwise according to circumstances.
The machine of the construction it may be considered as composed of the following parts
a machinery for communicating motion to the drying sieve, and the general

which is a story, was only performed in the winter months, to which musical
entertainment is best suited. The first will bear the name of the first, that is estimated
as being the best, as one of the best and most of the members are
to be carried off by a funeral pyre, with funeral Bompas or registers for
the dead.

On the outside of the case or walls which enclose the drying
chamber water is applied which receives a rotary motion from
a shaft having projecting cams or teeth which by
means of the ends of the long wires give them
a tendency along them. There is a
series of such cams on the end of a
shaft. The drying chamber has an
opening which may be opposite and gives access
to the grain from the top or
from the underlaying screen. In order to pull on

and the Office for Recording
Deeds and Titles to be City County of Rio Grande.
